FOLDING PUSH CHAIR

George Thomas, Hayes, England

Application April 15, 1949, Serial No. 87,800

2 Claims. (Cl. 280—38)

1

This invention relates to folding push chairs of the kind comprising a folding back, seat and arms which are adapted to be collapsed into a compact form when the chair is not in use so as to resemble closely an attache or suit case which can be easily carried.

More particularly the present invention is concerned with improvements in a folding push chair wherein the ground wheels of two pairs of ground wheels provided respectively at the front and back of the chair, are each mounted on an axle bracket and the four axle brackets thus provided (two at each side of the chair) are adapted to rotate about upright pivots carried by the end members of a bridge shaped frame extending transversely of the chair so that the wheels can be folded into the frame so as to be parallel to one another and extend in a transverse direction in the folded inoperative positions.

An object of the present invention is to provide an improved and more efficient construction of folding push chair.

According to the present invention there is provided a folding push chair of the kind referred to comprising in combination folding side frame members supporting the chair seat which are interconnected with upright pivots of the axle brackets in such a manner that they automatically impart a turning movement to said upright pivots to swing the axle bracket and wheels into and out of an operative position when the chair is opened out and collapsed respectively and means whereby a wheel of each pair of wheels is arranged to open earlier and close later than the other wheel so as to prevent the wheels of each pair of wheels at the front and the back fouling when opening and closing.

According to one embodiment of the invention the upright pivots of the axle brackets are fitted with toothed gear elements which are engaged by corresponding toothed gear elements mounted upon the folding side frame members which support the seat, the turning movement imparted to the gear elements during collapsing of the chair automatically effecting rotation of the upright pivots and the folding in of the wheels.

With another embodiment the side frame members at each side of the chair are connected by pivoted links with blocks which are slidable vertically on the upright pivots which are each formed with a helix so that the pivots are caused to turn with the movement of the blocks to swing the wheel brackets in and out during collapsing and opening of the chair.

One wheel of each pair of wheels at the front

2

and back of the chair is made to close before and open later than the remaining wheel so that the wheels do not foul one another during their movement. In the case of the arrangement employing gear wheels this is effected by fitting the gear wheels on the upright pivots of the axle brackets with dogs which co-act with a bar-like member fitted to the upper end of each upright pivot, the gear wheels being mounted loosely on the upper ends of the pivots so that no movement is transmitted to or permitted by the pivots until the dogs engage with or move away from the bar-like members on the gears, the dogs of one gear at each side of the chair acting on the bar-like member of that gear before or after the dogs of the other gear at the same side of the chair act on their associated bar member. The movement of the brackets is controlled by springs which operate to advance and retard the movement of said brackets.

When the upright pivots are formed with helices, the opening and closing of one wheel of a pair of wheels is effected by varying the pitch of the helices so that one has a quick start and the other a slow one.

In order that the invention may be clearly understood and readily carried into effect, reference will now be made to the accompanying drawings which illustrate two embodiments of the invention by way of example. In the drawings:

Figure 1 is a side elevation of the push chair erected.

Figure 2 is a view showing the chair collapsed.

Figure 3 is a front view, drawn to a larger scale of the part of the chair below the seat with the chair open.

Figure 4 is a fragmentary perspective view of the gear mechanism at one side of the chair.

Figure 5 is a detail sectional view of a gear at the upper end of one of the upright pivots.

Figures 6 to 8 are diagrammatic views illustrating the opening action of the wheel axles at one side of the chair.

Figure 9 is a detail perspective view of means for holding each axle bracket in an operative position.

Figures 10 and 11 are front and end views respectively of a modification in which sliding blocks engage with helices on the upright pivots, and

Figure 12 is a view similar to Figure 10 but showing the brackets turned inwards.

Referring to the drawings, the chair comprises a bridge shaped frame 1, which extends trans-

versely of the chair and each depending end wall 2 of the frame is formed with lugs 3 for receiving two oppositely directed L shaped axle brackets 4 for the ground wheels 5 at that side of the chair, the vertical limbs 6 of the brackets 4 being pivotally supported by the lugs 3 in the end walls 2 and the outer free ends of the horizontal portions 7 of the brackets receiving the wheels 5.

The upper end of each of the vertical limbs 6 of the wheel brackets 4 projects above the top 10 of the end wall 2 of the bridge 1 and is fitted with a gear wheel or toothed gear segment 8 which is turnable freely on the limb 6. The two gear wheels 8 thus provided at each side of the bridge 1 (see particularly Figure 4) are not in mesh but each is engaged by a gear segment 9 (when the push chair is collapsed) provided at the lower or inner end of normally upwardly and outwardly inclined frame members 10 for supporting the seat 11, the latter being provided with two such frame members 10 at each side of the chair.

The two gear segments 9 on the seat frame members 10 at each side of the chair are preferably in mesh to ensure that their movement is co-ordinated and to facilitate folding of the wheels 5.

To prevent the wheels 5 fouling each other when opening or closing, means are provided to make a wheel of each pair of wheels open earlier and close later than the other wheel. Such means may comprise two dog-couplings 12 which are fitted to each of the gear elements 8 and which have a degree of lost motion before positive engagement with a bar-like part 13 rigidly secured to the upper end of each vertical limb 6 of the pivoted axle brackets, the lost motion being controlled by springs 14 each of which is anchored at one end to the bar 13 on the respective axle bracket, and at its other end to the relatively stationary bridge 1, two of said springs 14 operating to advance, and another two acting to retard, the movement of the axle brackets 4. Such an arrangement ensures that one pair of wheels is partly opened before the other pair commence to move, and vice-versa.

The sequence of opening of two wheels 5 at one side of the push chair is illustrated diagrammatically by Figures 6 to 8.

Figure 6 illustrates the axle brackets 4 of two wheels in a closed or folded position. Now as the chair is opened and extended the two frame members 10 at that side of the chair are swung upwardly and the gear elements 9 turn the gear wheels 8. In the folded in position the right hand spring 14 as viewed in these figures is under tension so that as the gear 8 is turned in a clockwise direction the dogs 12 tend to move away from the associated bar 13 which follows the dogs round as the spring 14 re-asserts itself until the axle bracket reaches its extended position as shown in Figure 7.

As this action is taking place the other gear wheel 8 is turned by its associated element 9 in the reverse direction and in this case the spring 14 is closed and holds its bar 13 and the associated axle bracket 4 in the closed position until such time as the dogs 12 on this gear wheel 8 engage and turn the bar 13 and open the axle bracket against the influence of the spring 14 which is stretched. It will be seen that as the right hand axle bracket reaches its fully open position the dogs 12 of the other wheel 8 just commence to engage their bar 13 and open the other axle bracket 4. Completion of the operation results in the left hand bracket being fully opened out

as shown in Figure 8 and during opening out of the left hand bracket the dogs 12 of the right hand gear 8 have moved away from the associated bar 13. Thus in reverse action when the wheels 5 are being closed the dogs 12 on the left hand gear 8 move away from their bar and the spring 14 re-asserts itself to close the axle bracket whereas the dogs 12 of the right hand gear have an idle movement before they engage their bar to close the axle bracket against the influence of the spring 14 which is then tensioned again ready for a subsequent opening operation.

In the modification illustrated by Figures 10 to 12 upward and downward movement of the frame members 10 is transmitted to the wheel brackets 4 by a nut or block 15 which is acted upon by a link 16 connected between the block 15 and the member 10. The vertical limb 6 of each wheel bracket is in this case made up of a square section bar which is twisted along its length to form a helix 17 of variable pitch. The helices 17 of the two vertical limbs 6 at each side of the chair comprise differing variable pitch so that one has a greater turning action at the beginning of its motion which lessens as it proceeds while the other has a slower turning action at the beginning and increases as it proceeds. Thus as the members 10 are swung downwardly from their positions in Figure 10 to the positions shown in Figure 12 the blocks 15 act so that one turns and folds an axle bracket in quickly and the other folds its axle bracket in slowly. The gears 9 on the frame members 10 are preferably retained to ensure the members move in synchronism.

In both embodiments it is to be appreciated that the movement of the wheels 5 on the other side is complementary, i. e. one front wheel moves inwards to a collapsed position followed by the other front wheel, the latter opening first when the chair is opened out. The two rear wheels operate similarly.

The present invention also provides improved means for locking the ground wheels 5 in the open and operative position. Such means consists of a footrest 18 mounted on a substantially rectangular frame 19 which is pivoted between its ends at 20 to the lower ends of the side members 2 of the bridge member 1. When the chair is collapsed this footrest 18 and its frame 19 is located vertically within the bridge shaped frame 1 and held by releasable catch means and when the wheels 5 are moved to an open operative position this footrest frame 19 pivots to a horizontal position in which a part of it having the foot-board 18 projects forwardly beyond the front of the bridge shaped member 1 and between the front wheels 5 and a part rearwardly behind the bridge shaped member and between the rear wheels 5.

Upon these forwardly and rearwardly directed parts of the footrest frame are fitted hook-shaped members 21 (see Figure 9) adapted to engage the horizontal portions 7 of the axle brackets so that these brackets with the wheels 5 are held positively in position during the wheeling of the chair. The footrest frame 19 is also fitted with cam members 22 which act to guide the members 7 into the hooks 21. As the footrest pivots at 20, the rear hooks open upwards and the front ones downwards.

Figure 2 shows the chair in its collapsed position in which it can be carried about like an attache case. It will be noted that the back 23 and the seat 11 cover the two sides respectively

and a slot in the bottom part of the back material registers with a handle 24 on the bridge member 1 so that this handle 24 can be engaged when carrying the collapsed chair around.

I claim:

1. The combination in a collapsible push chair of a bridge shaped frame, depending end walls thereon, axle brackets having vertical and horizontal limbs, a pair of wheels mounted on each horizontal limb, pivoted supports for the vertical limbs on said end walls, folding side frame members, a seat supported by the frame members, gear segments on said frame members, gear elements turnable freely on the vertical limbs engaging the gear segments to impart a turning movement to the axle brackets to swing these and the wheels into and out of operative position when the chair is opened out and collapsed respectively, a lost motion device consisting of dog couplings fitted to each of the gear elements

10
15
20

and a bar-like part rigidly secured to the upper end of each vertical limb, springs controlling said lost motion device, whereby a wheel of each pair of wheels opens earlier and closes later than the other wheel.

2. In the combination according to claim 1, a footrest device and means thereon for locking the ground wheels in the open and operative position.

GEORGE THOMAS.
